CLAIM

I claim the ornamental design for a combined barbecue smoker and grill, as shown and described.

DESCRIPTION

FIG. 1 is a left isometric view of a combined barbecue smoker and grill showing my new design;

FIG. 2 is an isometric view of the rear and right side thereof; FIG. 3 is a rear elevational view thereof;

FIG. 4 is a left isometric view thereof, showing the smoker firebox door in an open position;

FIG. 5 is an isometric view of the front and left side, the lid is shown in an open position and the unclaimed headlight in a rotated position;

FIG. 6 is an isometric view thereof; and,

FIG. 7 is an enlarged view of the headlight shown in FIG. 6. The broken lines shown in the drawings are for illustrative purposes only and do not form part of the claimed design. The surface shading (shown in uniformly spaced horizontal and vertical lines) does not represent a pattern.
